US0D1083443S

(12) **United States Design Patent** (10) Patent No.: **US D1,083,443 S**
(45) Date of Patent: ** Jul. 15, 2025

(54) **MATTRESS**

(71) Applicant: **Sleep Number Corporation**,
Minneapolis, MN (US)

(72) Inventors: **Natalie Negus**, Minneapolis, MN (US);
Antony Kirk, Minnetonka, MN (US)

(73) Assignee: **Sleep Number Corporation**,
Minneapolis, MN (US)

(**) Term: **15 Years**

(21) Appl. No.: **29/719,090**

(22) Filed: **Dec. 31, 2019**

(51) LOC (15) Cl. **06-09**
